UNITED STATES PATENT OFFICE.

STEPHEN A. DAVIS AND ROBERT BLAKE, OF NEWARK, N. J., ASSIGNORS
TO THE SUPERIOR DRIVE SCREW COMPANY, OF NEW YORK, N. Y.

MACHINE FOR SWAGING SCREW-THREADS.

SPECIFICATION forming part of Letters Patent No. 279,353, dated June 12, 1883.

Application filed May 11, 1882. (No model.)

To all whom it may concern:

Be it known that we, STEPHEN A. DAVIS and ROBERT BLAKE, of Newark, in the county of Essex and State of New Jersey, have invented a new and Improved Screw-Swaging Machine, of which the following is a description in such full, clear, concise, and exact terms as to enable any one skilled in the arts to which our invention belongs to make and use the same, reference being had to the accompanying drawings, making part of this specification, and to the figures and letters of reference marked thereon.

Figures 1 and 2 of said drawings are vertical longitudinal sections through said machine, both taken upon the same plane, but showing the machine set in opposite positions. Figs. 3 and 4 are both top views of the machine, but show it set in opposite positions, Fig. 20 corresponding to Fig. 5, and Fig. 4 to Fig. 2. Fig. 5 is an elevation of the right-hand end of the machine, showing it in the position it appears in Fig. 2. Figs. 6 and 7 are several views of thread-swaging dies, hereinafter more fully described.

Our invention consists of an improved screw-swaging machine, the construction and operation of which will be readily understood from the following description, the points of novelty being designated in the claims concluding this specification.

Reference being had to Fig. 2 of the drawings, *o* is a screw-shank held by a split chuck, *N*, carried by a rotating and reciprocating sleeve, *M*, set in a reciprocating head-block, *C*, operated by a crank-pin, *V*, set between a pair of crank-wheels, *T T'*, and connected to the head-block by means of the connecting-rod *S*. The split chuck *N* is made to open and close upon the screw-blank by means of a slot-cam, *G*, in which it is made to move by the motion of the head-block, the chuck being drawn back into the sleeve and upon the blank when the machine is in a position shown by the figure referred to, the cam *G* imparting to the chuck a motion endwise, by which it is thrust out and drawn back into the sleeve by the reciprocating motion of the head-block *C*. To give the sleeve *M* a rotating motion, cogs 50 *M'* are cut in its periphery, into which the cog-wheel *A* gears, the cogs in the sleeve be-

ing made in length equal to the width of the wheel *A*, plus the distance the sleeve is to travel endwise. The reciprocating or endwise motion of the sleeve is obtained by means of a screw-thread, *K*, cut on its rear end, and made to screw into a corresponding thread cut in the head-block *C*, the sleeve being thus made to move endwise at the same time it is made to rotate about its own axis. The rotary motion of the sleeve *M* is transmitted from a cog-rack, *G'*, bolted to the frame of the machine, and into which gears a pinion-wheel, *E*, upon the end of the shaft *B*, upon which the wheel *A* is also fixed, and which has its journal-bearing in the head-block *C*, by which it is carried. By these means it will be seen that by the motion of the crank *V* the head-block *C* will be given a reciprocating motion, the pinion *E* a reciprocating and rotary motion in the cog-rack *G'*, which motion will also be imparted to the wheel *A*, which will in its turn impart a rotary motion and an endwise motion to the sleeve *M* at the same time it is reciprocating with the head-block. These several parts and motions being understood, assume the screw-blank to be clamped in the position shown by Fig. 2. The head-block, as it is moved forward by the crank *V*, will carry the screw-blank over the long stationary swaging-die *Q'*, and at the same time the blank will be rotated by the cog-wheel *A* and move back endwise by the screw-thread *K*, or other device adjusted to give the desired pitch to the thread to be cut in the screw-blank.

Having thus provided for holding the screw-blank, and giving it the proper motion over the stationary swaging-die *Q'*, we make a corresponding die, *Q*, and set it into a slide-bearing exactly opposite the die *Q'*, as shown in Fig. 5, adjusting the cutting-edges of the two dies at a proper angle in relation to each other to form the desired thread on the screw.

Having thus made and adjusted the die *Q*, we impart to it a reciprocating motion over the die *Q'* by means of a crank, *W*, set in a crank-wheel, *T''*, and a connecting-rod, *S'*, causing the die *Q* to travel far enough each way over the die *Q'* to clear the discharge-holes *R*, through which the screw drops when it is discharged out of the clamp *N*.

Now let the machine be in the position shown

by Fig. 2, and let the head-block move forward, carrying the screw-blank over the die Q'. The die Q will also move forward upon the screw-blank, compressing it between the two dies and swaging the thread on it by the pressure of the dies and the motion of the screw-blank, the finished screw being discharged, when it reaches the opposite end of the die Q', by the cam G, the chuck N being then thrust forward in the position shown by Fig. 1, allowing the clamp to spring open and release the screw. As soon as the screw is discharged the head-block commences its return motion, a succeeding blank drops in place, and the operation is repeated *ad infinitum*.

In the operation above described it will be observed that the chuck N moves back endwise with the sleeve, and is thus made to retain the blank, notwithstanding the endwise motion of the sleeve, the sleeve and chuck moving together until the thread is formed, the cam then throwing the chuck forward and releasing the screw. The arrangement for feeding the screw-blanks in the clamp is not shown in the drawings, as it forms no part of the invention making the subject-matter of this specification. It is proper to add, however, that the slot-cam G is cut in two long stationary blocks, set far enough apart to allow the body J of the chuck to travel between them, the head L of the chuck only traveling into the grooves forming the cam, thus leaving the upper end of the chuck always open to receive the screw-blanks.

35 By Figs. 6 and 7 of the drawings are shown the dies in detail, which may be made in the form shown or of such other form as may be required to carry out the purpose of the invention.

40 In concluding this specification, we observe that the invention is quite as applicable to the manufacture of screw-bolts as to wood-screws, and we intend to embrace in the following claims the above-described machine for making the thread on all sorts of metal screws. The features that distinguish this screw-swaging machine from all others of its class are found in the fact that the thread is swaged between the top and bottom die, each of which has a single edge corresponding with the form of

the thread, both dies being set on the same plane, and the pitch of thread being formed by the mechanism that carries the screw-blank. In this machine only one convolution of the thread is cut at each revolution of the screw-blank, and the pitch of that convolution is not formed by the dies, but by the machinery that carries the blank. The blank has a rotating and a lateral movement independent of the dies that swage the thread and that govern the formation of the thread.

The chuck that carries the screw-blank may of course be modified in a variety of ways. Thus, for example, instead of making the clamp open when pushed forward by a cam, one may be employed which is forced back by a spring as soon as it reaches the end of the die, thus instantly releasing the screw.

Having thus described our invention, we claim—

1. In a screw-swaging machine, two thread-swaging dies, one moving opposite the other, and each having a single edge, by which a crease is swaged in the blank, in combination with a blank-chuck having a rotating and a lateral endwise motion, by which the crease is made in the form of a helix or screw-thread on the blank.

2. In a screw-swaging machine, the combination of a reciprocating head-block, C, a chuck, N, a chuck-sleeve, M, and a chuck-cam, G, the several parts coacting substantially as described.

3. In a screw-swaging machine, the combination of a reciprocating head-block, C, a clamping device, N, for the screw-blank, and a stationary cam, G, to operate the clamping device, substantially as described.

4. In a screw-swaging machine, the combination of a stationary cog-rack, G', a stationary cam, G, a reciprocating head-block, C, carrying a clamping-chuck, N, and a cog and pinion wheel, A E, the several parts coacting substantially as described.
